UNITED STATES PATENT OFFICE.

CHARLES A. OLSON AND CLAUDE H. TOOMBS, OF GENEVA, ILLINOIS.

WRENCH.

1,243,861.

Specification of Letters Patent. Patented Oct. 23, 1917.

Application filed June 12, 1916. Serial No. 103,123.

To all whom it may concern:

Be it known that we, CHARLES A. OLSON and CLAUDE H. TOOMBS, both citizens of the United States, and both residing at Geneva, in the county of Kane and State of Illinois, have invented new and useful Improvements in Wrenches, of which the following is a clear, full, concise, and exact description, reference being had to the accompanying drawing, forming a part of this specification.

Our invention relates to wrenches.

One of the objects of our invention is to provide an improved wrench which, when not in use, can be folded compactly and which will be simple, durable in construction, and efficient in use.

In the drawings, in which one embodiment of our invention is shown—

20 Figure 1 is a side elevation of the improved wrench showing the parts in position for use;

Fig. 2 is a side elevation of the wrench with parts folded;

25 Fig. 3 is a section on the line 3—3 of Fig. 1;

Fig. 4 is a section on the line 4—4 of Fig. 3 showing the manner in which the holder is mounted on the brace; and

30 Fig. 5 is an elevation showing part of the brace and holder.

Referring to the drawings in detail, the wrench shown comprises a brace 10 by means of which the wrench can be operated, a pair of gripping jaws 11 for holding a nut and the like, and a holder 12 for the jaws 11 connected with the brace 10.

The brace 10 is provided with the usual handles or grips 13 and 14 and with the U-shaped crank member 14^a on which the grips are rotatably secured. The holder 12 has such a connection with the brace that it can be swung from the position shown in Fig. 1 to the position shown in Fig. 2, and the connection is such that the holder will be securely held in either of these two positions. To accomplish this the holder 12 has a square opening 15 in one side to receive a head 16 secured on the lower arm of the brace. This head has a rounded portion 17 and a squared portion 18, these two portions being alternately movable into the opening 15.

When the portion 17 lies within the opening 15 the holder 12 can be rotated about the lower arm of the brace 10 as an axis,

but when the squared portion 18 lies in the opening 15 the holder is held from rotation with respect to the brace. A spring 19 located within the holder 12 surrounds the 60 lower arm of the brace, bears against the head 16 and tends to normally hold the squared portion 18 of the head within the opening 15. A pin 19 extends through the head 16 and limits the distance to which the 65 spring 19 can force the portion 18 within the opening 15, by coming in contact with the inside of the holder 12. The holder 12 comprises a sheet metal tube having slots 70 21 in opposite sides to receive and guide the ends of a pin 22 which forms a pivot for the jaws 11. These jaws 11 are each provided with a half round bearing part 23 to receive the pin 22. A spring 24 is located between the jaws 11 which holds the 75 jaws 11 normally apart as far as the holder 12 will permit. The lower end of each jaw is provided with a rectangular recess 25 for engaging a nut.

To fold the wrench from the position 80 shown in Fig. 1 to the position shown in Fig. 2 the holder 12 is moved, with respect to the brace 10, against the pressure of the spring 19 until the squared portion 18 is out of the opening 15. The holder 12 is then rotated about the lower arm of the brace 10 to the position shown in Fig. 2 where it lies substantially between the upper and lower arms of the brace so that it occupies very little space.

Having thus described our invention what we claim as new and desire to secure by Letters Patent is:—

1. In a device of the class described a brace having upper and lower arms and a 95 portion connecting said arms, gripping means, and a holder for said gripping means connected to said brace, said holder having a non-circular opening therein, and a non-circular member fitting said opening and 100 non-rotatable with respect to said lower arm and movable into and out of said opening, the connection being so constructed that the holder can be swung about said lower arm as an axis from a position substantially outside of the arms of the brace to a position 105 substantially between said arms.

2. In a device of the class described a brace having upper and lower arms and a portion connecting said arms, gripping means, and a holder for said gripping means connected to said brace, said holder comprising

ing a tubular member having openings in opposite sides thereof through which said lower arm extends, one of said openings being non-circular, and a non-circular member fitting said opening and non-rotatable with respect to said lower arm and movable into and out of said opening, the connection being so constructed that the holder can be swung about said lower 10 arm as an axis from a position substantially outside of the arms of the brace to a position substantially between said arms.

3. In a device of the class described a brace having upper and lower arms and a portion connecting said arms, gripping means, and a holder for said gripping means connected to said brace, said holder comprising a tubular member having openings in opposite sides thereof through which 15 said lower arm extends, one of said openings being non-circular, and a member fixedly secured with respect to said lower arm and slidable in said non-circular opening and having a first portion rotatable in 20 said opening, and a second portion non-rotatable in said opening, said portions being alternatively movable into said opening, the connection being so constructed that the holder can be swung about said lower arm 25 as an axis from a position substantially outside of the arms of the brace to a position substantially between said arms.

4. In a device of the class described a brace having upper and lower arms and a portion connecting said arms, gripping means, and a holder for said gripping means connected to said brace, said holder comprising a tubular member having openings in opposite sides thereof through which 30 said lower arm extends, one of said openings being non-circular, and a member fixedly secured with respect to said lower arm and slidable in said non-circular opening and having a first portion rotatable in 35 said opening and a second portion non-rotatable in said opening, said portions being alternatively movable into said opening, and spring means tending to hold said second portion in said opening, the connection being 40 so constructed that the holder can be swung about said lower arm as an axis from 45 said opening and a second portion non-rotatable in said opening, said portions being alternatively movable into said opening, and spring means tending to hold said second portion in said opening, the connection being 50 so constructed that the holder can be swung about said lower arm as an axis from

a position substantially outside of the arms of the brace to a position substantially between said arms.

5. In a device of the class described a brace having upper and lower arms and a portion connecting said arms, gripping means, and a holder for said gripping means connected to said brace, said holder comprising a tubular member having openings in opposite sides thereof through which 55 said lower arm extends, one of said openings being non-circular, and a member fixedly secured with respect to said lower arm and slidable in said non-circular opening and having a first portion rotatable in said opening and a second portion non-rotatable in 60 said opening, said portions being alternatively movable into said opening, and spring means tending to hold said second portion in said opening, said spring means including a coil spring within said tubular member surrounding said lower arm, the connection being so constructed that the holder can be swung about said lower arm 65 as an axis from a position substantially outside of the arms of the brace to a position substantially between said arms.

6. In a device of the class described a brace having upper and lower arms and a portion connecting said arms, gripping means, and a holder for said gripping means connected to said brace, said holder comprising a tubular member having openings in opposite sides thereof through which 70 said lower arm extends, one of said openings being non-circular, and a non-circular member fitting said opening and non-rotatable with respect to said lower arm and movable into and out of said opening, said gripping means including a pair of jaws 75 slidably mounted in said tubular member, the connection being so constructed that the holder can be swung about said lower arm as an axis from a position substantially outside of the arms of the brace to a position substantially between said arms.

In witness whereof, we have hereunto subscribed our names.

CHARLES A. OLSON.
CLAUDE H. TOOMBS.
